UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

DYNAMO-ELECTRIC MACHINE.

SPECIFICATION forming part of Letters Patent No. 259,617, dated June 13, 1882.

Application filed December 13, 1881. (No model.)

To all whom it may concern:

Be it known that I, EDWARD WESTON, a subject of the Queen of Great Britain, and a resident of Newark, in the county of Essex and 5 State of New Jersey, have invented certain new and useful Improvements in Dynamo-Electric Machines, of which the following is a specification, reference being had to the drawings accompanying and forming a part of the 10 same.

My invention is designed as an improvement on the machines shown and described in former patents granted to me and in applications by me made, the main object of the improvement being to render the said machines better suited for the purposes of incandescent lighting, electroplating, or other and similar purposes; and to this end the invention consists in a novel method of winding the conductors 15 forming the coils of the revolving armature and forming the connections from the same to the commutators, as will be more fully herein-after described.

In the accompanying drawings, illustrative 20 of the invention, Figure 1 is a sectional view of a complete armature with its appurtenances, the coils of which are wound and connected to the commutators in accordance with my present invention. Fig. 2 is a diagrammatic illustration 25 of the method of winding and connection as employed in the systems invented by me, to which reference is made above; and Fig. 3, a similar diagram, illustrative of my present improvement.

The armatures constructed in accordance 30 with my former patents consist in the main of a cylindrical core composed of magnetic plates, with interposed disks of insulating material, in which grooves or recesses parallel 35 with the axis are cut for the reception of the coils. These latter are wound in sections in diametrically-opposite recesses, and the several 40 sections connected by loops, from which connection is made to the segments of the commutator. Each section or division of the coil 45 has thus its corresponding segment, and as those segments on opposite sides of a line bisecting the commutator through the neutral points are of opposite polarity, it is evident

that if collecting-brushes be applied to the segments at or near the neutral points the result is a machine the electro-motive force of which is the aggregate electro-motive force of the total number of sections of coil on the armature divided by two. In order, therefore, to 55 render these machines capable of producing currents of less intensity and greater quantity, and at the same time secure the other advantages accruing from the described method of construction, I take off loops from the several 60 sections of conductor at two points instead of one, employing for this purpose two commutators and two sets of collecting-brushes. The loops must be taken off from the sections at such points as will insure an equal division of 65 the current between them; so, in order that this may be done without having both commutators at the same end of the armature, the sections or coils are formed with an odd number 70 of turns. In this case the loops from any given section will be diagonally opposite each other with respect to the core upon which said coils or sections are wound. This will be understood 75 by reference to Figs. 2 and 3. In Fig. 2 a section of continuously-wound coil is shown, the loops taken at the junction only of each coil with the next, and represented by *a a*. This coil, as is well known, is wound continuously 80 about the armature and upon itself until a complete circle of loops is formed. In Fig. 3 the same system of winding is followed; but two loops, *b c*, are here taken off at the junctions between the several coils and also from the middle of each coil. Loops thus formed are in 85 the same coil at all times of opposite polarity.

When heavy wires are used they may be cut wherever it is desired to form a loop to avoid bending, and instead of winding the coils back on themselves, as is done in other forms, each one may be formed successively and separately 90 alongside of each other.

In Fig. 1 the core is shown as composed of the perforated plates *A*, fixed on a shaft, *B*, and separated from each other by the thin disks of insulating material *C*. Upon the cylindrical 95 surface of this core, or in grooves cut for their reception, the coils *D D* are wound, the connections from each being made, as above described,

by means of the loops or united ends *b c* to arms *E*, forming part of the commutator-segments.

From this machine two separate currents may be taken and applied to different purposes, or 5 the two sets of brushes may be connected together to give a single current, the brushes being joined either in multiple arc or in series.

Having thus described my invention, what I claim as new, and desire to secure by Letters 10 Patent, is—

1. A cylindrical armature for dynamo-electric machines, wound with a double system of continuous coils in separate divisions, in combination with two independent commutators,

connected respectively with loops taken from 15 diagonally-opposite portions of the said divisions, substantially as described.

2. An armature wound with a double system of continuous coils in separate divisions, in combination with two independent commutators, connected respectively with loops taken from the junctions of the several divisions of coils, and from the middle of each of said divisions, substantially as set forth.

EDWARD WESTON.
